DESIGN FOR A SEWING MACHINE

Leonard C. Marsac, Cranford, and Wilbur J. Peets,
Elizabeth, N. J., assignors to The Singer Manufacturing Company, Elizabeth, N. J., a corporation of New Jersey

Application April 24, 1947, Serial No. 138,582

Term of patent 14 years

(Cl. D70—1)

To all whom it may concern:

Be it known that we, Leonard C. Marsac and Wilbur J. Peets, citizens of the United States, residing respectively at Cranford and Elizabeth, in the county of Union and State of New Jersey, have invented a new, original, and ornamental Design for a Sewing Machine, of which the following is a specification, reference being had to the accompanying drawings, forming a part thereof.

In the drawings,

Fig. 1 is a front perspective view of a sewing machine showing our new design.

Fig. 2 is a rear perspective view of the sewing machine shown in Fig. 1, and

Fig. 3 is an end elevational view of the sewing machine shown in Figs. 1 and 2.

We claim:

The ornamental design for a sewing machine, substantially as shown.

LEONARD C. MARSAC.
WILBUR J. PEETS.
